(57) **CLAIM**

The ornamental design for a data accessing device, as shown and described.

DESCRIPTION

FIG. 1 is a perspective view of a data accessing device showing the claimed design;

FIG. 2 is a front elevational view of FIG. 1;

FIG. 3 is a rear elevational view of FIG. 1;

FIG. 4 is a left side elevational view of FIG. 1;

FIG. 5 is a right side elevational view of FIG. 1;

FIG. 6 is a top plan view of FIG. 1;

FIG. 7 is a bottom plan view of FIG. 1;

FIG. 8 is an enlarged view of the portion indicated by the square A of FIG. 1;

FIG. 9 is an enlarged view of the portion indicated by the square B of FIG. 1; and,

FIG. 10 is a perspective view showing the data accessing device of the claimed design in the usage state.

The broken lines in the drawings represent unclaimed subject matter and form no part of the claim.
